UNITED STATES PATENT OFFICE.

ALDEN L. PUTNAM, OF DETROIT, MICHIGAN, ASSIGNOR TO DETROIT PRESSED STEEL COMPANY, OF DETROIT, MICHIGAN, A CORPORATION OF MICHIGAN

METHOD OF FORMING A PRESSED-SHEET-METAL ARTICLE.

1,249,825.

Specification of Letters Patent. Patented Dec. 11, 1917.

Application filed January 31, 1916. Serial No. 75,365.

To all whom it may concern:

Be it known that I, ALDEN L. PUTNAM, a citizen of the United States of America, residing at Detroit, in the county of Wayne and State of Michigan, have invented certain new and useful Improvements in Methods of Forming a Pressed-Sheet-Metal Article, of which the following is a specification, reference being had therein to the accompanying drawings.

The invention relates to the manufacture of articles from pressed sheet metal, and it is the primary object of the invention to obtain an advantageous distribution of the metal with a variation of the thickness or gage of different portions corresponding to the stresses to which they are subjected. In the present state of the art a great variety of shapes have been pressed from flat sheet metal blanks and the gage or thickness of the metal in the different portions is increased or diminished according to whether there is an upsetting or expanding action. The distribution thus obtained is not, however, always an advantageous one and as a result some portions are relatively weak and others over-strong. With the present invention I have overcome this defect by producing a predetermined distribution of the metal so as to form a blank of varying gage or thickness and in then pressing the blank to the desired form.

In the drawings:

Figure 1 is a plan view of the blank;

Fig. 2 is a cross section thereof;

Fig. 3 is a perspective view of the pressed blank;

Fig. 4 is an elevation of a connecting rod formed of complementary pressed sections;

Figs. 5 and 6 are longitudinal sections thereof in planes at right angles to each other; and

Fig. 7 is a cross section on line $x-x$ Fig. 5.

In carrying out my invention the article to be pressed is first designed with the proper variation in the thickness of the metal in different portions to secure the greatest strength. The flat blank is then designed with a varying thickness or gage such as to produce the desired distribution when pressed to the proper form. The blank so designed may be formed by any suitable process, such as rolling or pressing, but preferably by a rolling process. To form the

specific article illustrated in the drawings a blank is required in which the opposite end portions are of greater thickness than the central portion, the metal being tapered from the thicker to the thinner portions so as to avoid any points of abrupt change. As shown in Fig. 1, the blank A which may be formed by rolling has a central portion B of relatively light gage, an edge portion C of heavier gage and an opposite edge portion D of still heavier gage, while intermediate tapering portions E and F unite the portions C and D respectively to the portion B. From this blank, which may be rolled in a continuous strip the individual blanks for forming connecting rods are cut, as indicated by the dotted lines G. This will form of the portion C the smaller or wrist-pin bearing and of the portion D the larger bearing, while the tapering portions E and F unite these bearings with the central rounded shank portion. The rod is formed of a pair of complementary sections such as just described, which are then placed with their edges abutting and are welded or otherwise secured to each other, as indicated by the line H.

A rod formed as just described is not only lighter than one formed from uniform gage of metal, but is also greatly increased in strength per unit of weight, and the fact that the metal may be reinforced in gage where necessary dispenses with the necessity of complex die work and pressing operations.

What I claim as my invention is:

1. The method of forming pressed sheet-metal articles, comprising the forming of a substantially flat blank of varying gage in different portions thereof having predetermined relation to each other, and die-pressing the blank to re-fashion and re-distribute the metal thereof.

2. The method of forming pressed sheet-metal articles, comprising the varying of the gage of a substantially flat blank to distribute the metal thereof with reference to a re-fashioned form, and die-pressing the blank to re-fashion and re-distribute the metal thereof.

3. The method of forming pressed sheet-metal articles, comprising the varying of the gage in a continuous blank to form portions of different thickness connected by intermediate tapering portions, and die-pressing the

- blank to re-fashion and re-distribute the metal thereof.
4. The method of forming pressed sheet-metal articles, comprising the rolling of a continuous sheet to distribute the metal and vary the gage in different portions thereof, and the die-pressing of articles from said blank to re-fashion and re-distribute the metal thereof.
- 10 5. The method of forming pressed sheet-metal articles, comprising the varying of the gage in different portions of a continuous sheet-metal strip, cutting blanks from said strip, and die-pressing the same to re-fashion and re-distribute the metal thereof.
- 15 6. The method of forming connecting rods, comprising the rolling of a blank with end portions of greater thickness than the intermediate portion and die-pressing said blank to form the heads or bearings of the rod 20 from the thicker end portions and the shank of the rod from the thinner intermediate portion.
7. The method of forming connecting rods, comprising the rolling of a blank with end 25 portions of greater thickness than the intermediate portion and with tapering portions connecting said end and intermediate portions, and die-pressing said blank to form the bearings or heads of the rod from 30 the thicker portions, the rod proper or shank from the thinner intermediate portion and the ends of said shank which join the heads from the tapering portion.

In testimony whereof I affix my signature. 35
ALDEN L. PUTNAM.
